ROTATION INDICATOR FOR HOIST DRUMS

Herbert W. Dow, Milwaukee, Wis., assignor to
 Nordsberg Manufacturing Co., Milwaukee, Wis.,
 a corporation of Wisconsin

Application September 23, 1946, Serial No. 698,681

5 Claims. (Cl. 74—802)

1

This invention relates to position indicators for hoists of the type used in mines.

In such hoists the hoisting cable is wound on a helically grooved drum and the position of the hoist cage is customarily indicated by a so-called "miniature." This comprises a dial graduated according to "levels" and a hand which swings over the dial and is driven by a motion-reducing gear train from the drum. The hand indicates on this dial the position of the drum and consequently the level of the cage.

A common practice is to use two drums coaxially mounted on the same shaft and two cages each with its own cable so arranged that when the two drums turn together one cage is raised and the other is lowered. To use such an arrangement to hoist from different levels in the mine shaft only one drum can be fixed to the hoist shaft. The second drum must be clutched to the shaft and must have its own "miniature." As a practical matter the clutch is at the end of the drum, and if the drums are set close together, as is commonly desirable, connection of the miniature drive for the second or clutched drum is a matter of considerable difficulty.

The present invention offers a very simple solution of the problem, using a planetary gear train in which the planet pinion unit is journaled in the clutch spider and comprises pinions which turn together and engage respective sun gears, one on the drum and the other turning freely coaxially with the drum outside the clutch. If the ratios of the planet pinions to their respective sun gears are equal, the sun gears will have identical motion characteristics, and the second may be used to drive a miniature indicating the position of the second drum and consequently the position of its cage.

Theoretically, the planetary train could take various forms, but where the clutch spider shifts axially, its motion can be accommodated by using spur pinions and spur toothed sun gears, so dimensioned that they mesh continuously despite axial displacement of the planet pinions. Such is the preferred construction which will now be described by reference to the accompanying drawings.

In the drawings:

Fig. 1 is a plan view of a two-drum hoist with two miniatures, one for each drum, that for the clutched drum being driven by means embodying the invention.

Fig. 2 is an enlarged view partly in section, showing the left hand portion of Fig. 1.

Fig. 3 is a section on the line 3—3 of Fig. 2.

2

In Fig. 1 a base is indicated at 6. On this are mounted bearings 7 for the hoist shaft 8 which is driven by any suitable means, not shown.

Fixed on shaft 8 is a hoist drum 9 with brake drum 11 formed integrally with it at its outer end. The brake which coats with drum 11 is not illustrated. Freely rotatable on shaft 8 is a second hoist drum 12, which likewise has an integrally formed brake drum 13. The brakes for this drum are not illustrated. The drums 9 and 12 are closely spaced and the shaft is unsupported between bearings 7.

Drum 12 is supported by end spiders, one of which appears at 14 in Fig. 2. The hub of this 15 spider turns on journal 15. The hub 16 of a clutch spider 17 is mounted on a prismatic portion 18 of shaft 8 so as to be slidable axially to engage and disengage the clutch. It is moved by a shifter not shown, but engaging groove 20 19 in the hub 16 of the spider. The clutching mechanism is within brake drum 13 and may take 25 any preferred form. To afford the simplest practicable illustration the drawings (Fig. 2) show a dental clutch, one dentated element of 25 which is the rim of spider 17 and the other is a ring carried by spider 14.

So far as the invention is concerned, the only material point as to the clutch is that spider 17 is shifted axially in one direction to connect 30 shaft 8 and drum 12, so that they rotate together, and is shifted in the opposite direction to release them so that they may rotate independently.

The mechanism so far described is simply one known type of hoist to which the invention may 35 be applied.

Mounted on the hub of spider 14 of drum 12 is a flanged annulus 21 carrying a spur sun-gear 22 which is coaxial with shaft 8 and drum 12. Freely rotatable between confining flanges 23, 40 24 on shaft 8 outside the hub 16 of the clutch spider is a ring 25 which carries a spur sun gear 26 of the same pitch diameter as sun gear 22 and coaxial with shaft 8. The two gears are preferably identical.

45 Journaled in hub 16, with its axis parallel with the axis of shaft 8 is a planet gear shaft 27 to opposite ends of which are keyed substantially identical wide-faced pinions 28 and 29 which mesh with respective sun gears 22 throughout the axial shifting motion of 50 spider 17.

Because of the planetary gear train above described ring 25 always reproduces the rotary motion of drum 12, whether the clutch be engaged or not.

The ring 25 is constructed in two halves connected at 31. As a convenient way of driving the miniature a second gear 32 is formed in ring 25 and meshes with pinion 33 (see Fig. 3).

Referring to Fig. 1 the dial of the miniature for drum 12 appears at 34 and the hand at 35. The illustrated drive from gear 33 to the hand 35 is conventional and comprises a series of shafts 36 connected by miter gears in gear boxes 37.

The dial of the miniature for drum 9 appears at 38 in Fig. 1 and the hand at 39. A gear 41 on shaft 8 and a pinion 42 drive the hand 39 by connections essentially identical with those already described.

The use of a spur type planetary train, with wide faced gears, is important where the planet gears are mounted in an axially shiftable part. Either gear of a meshing pair, or both, could obviously be wide, so long as continuous meshing is assured. Weight is saved by making the small pinions wide faced, which is the reason for adopting the proportions shown.

Other types of planetary train can be evolved, some but not all of which are adaptable to constructions in which the planet gears must shift axially.

Consequently, the illustrated arrangement is described as the simplest and best, without, however, implying strict limitation of the invention thereto. A similar problem may arise where the clutch spider does not shift, a condition which would broaden the range of selection of planetary trains.

What is claimed is:

1. Means affording a continuous indication of the rotary movements of a first rotary member, at the remote end of a second and coaxial rotary member which at times rotates with and at other times rotates relatively to the first rotary member, comprising in combination with said rotary members a sun gear coaxial and turning with the first rotary member; a second and freely rotatable sun gear coaxial with the first sun gear and situated at that end of the second rotary member which is remote from the first rotary member; two planet gears journaled in the second rotary member, connected with each other to turn at equal angular velocities and meshing with respective sun gears; and means for indicating rotary motion of the second sun gear, the pitch-ratios of the two sun-planet trains being equal.

2. The combination defined in claim 1 in which the sun gears are spur gears of equal pitch diameters, and the planet gears are of equal pitch diameter and are connected to turn

as a unit on an axis parallel with the common axis of the two rotary members.

3. Means affording a continuous indication of the rotary movements of a first rotary member at the remote end of a second and coaxial rotary member which at times rotates with and at other times rotates relatively to the first rotary member, and is capable also of limited axial motion in the direction of the common axis of rotation toward and from the first rotary member, comprising in combination with said rotary members, a spur sun gear mounted coaxially with the first rotary member to turn therewith; a second and freely rotatable spur sun gear of the same pitch diameter as the first sun gear coaxial therewith and situated beyond that end of the second rotary member which is remote from the first rotary member; a pair of spur planet gears connected to turn at equal angular velocities and carried by the second rotary member in positions to mesh with respective sun gears, the ratios of the two sun-planet trains being equal; means serving to maintain meshed engagement of both planet gears with their respective sun gears irrespective of axial motion of the second rotary member; and means for indicating rotary motion of the second sun gear.

4. The combination defined in claim 3 in which one gear of each sun-planet train has a face sufficiently wide to accommodate the axial motion of the second rotary member while the gears remain meshed.

5. The combination defined in claim 3 in which the planet gears have each a face sufficiently wide to accommodate the axial motion of the second rotary member while remaining meshed with its sun gear.
